CLAIM

The ornamental design for a pepper grinder, as shown and described.

DESCRIPTION

FIG. 1 is a top and front view of a pepper grinder or the like, showing our new design;

FIG. 2 is a front elevational view thereof, the rear elevational view being a mirror image of the front view shown;

FIG. 3 is a right side elevational view thereof, the left side elevational view being a mirror image of the side view shown;

FIG. 4 is a top plan view thereof;

FIG. 5 is a bottom plan view thereof; and,

FIG. 6 is a cross-sectional view taken in the direction of the arrows on line 6-6 of FIG. 2.
